UNITED STATES PATENT OFFICE

114,172

DESIGN FOR A WALL CASE FOR PHONO- GRAPH RECORDS

Walter F. Brotzman and Benjamin Harry Statter,
Baltimore, Md., assignors to Display Center,
Baltimore, Md.

Application January 24, 1939, Serial No. 82,564

Term of patent 14 years

To all whom it may concern:

Be it known that we, Walter F. Brotzman and Benjamin Harry Statter, citizens of the United States, residing at Baltimore, in the State of Maryland, have invented a new, original, and ornamental Design for a Wall Case for Phonograph Records, of which the following is a specification, reference being made to the accompanying drawing, forming a part thereof, in which the figure is a perspective view in elevation of the wall case for phonograph records showing our design.

We claim:

The ornamental design for a wall case for phonograph records, as shown.

WALTER F. BROTZMAN.
BENJAMIN HARRY STATTER.
